(57) **CLAIM**

The ornamental design for a chair for outdoors, as shown and described.

DESCRIPTION

FIG. 1 is a top perspective view of a chair for outdoors; FIG. 2 is a right-side elevational view of the chair for outdoors shown in FIG. 1;

FIG. 3 is a front elevational view thereof;

FIG. 4 is a top plan view thereof;

FIG. 5 is a rear elevational view thereof; and,

FIG. 6 is a bottom plan view thereof.

The broken lines shown in the drawings illustrate portions of the article that form no part of the claimed design. A left-side elevational view is not shown because it is a mirror image to the right-side elevational view shown in FIG. 2.
